GEORGE W. ELSEY, OF ANDERSON, INDIANA, ASSIGNOR TO GENERAL MOTORS CORPORATION, A CORPORATION OF DELAWARE.

ENGINE-STARTING APPARATUS.

Application filed December 19, 1924. Serial No. 757,068.

This invention relates to engine starting apparatus and more particularly to the type of apparatus including an electric motor which drives a pinion normally demeshed from a gear connected with the engine. One type of such apparatus provides means for manually engaging the gears and for closing a switch to cause the motor to operate to crank the engine. In such apparatus means are generally provided for permitting the closing of the motor switch prior to actual meshing of gears in case the ends of the motor pinion teeth should collide with the ends of the engine gear teeth. In this way the motor is caused to operate before gear meshing in order to register the pinion teeth with the tooth spaces of the engine gear.

One of the objects of the present invention is to simplify the construction of the means referred to in order that cost of manufacture of starting apparatus may be materially reduced.

Further objects and advantages of the present invention will be apparent from the following description, reference being had to the accompanying drawings, wherein a preferred form of embodiment of the present invention is clearly shown.

In the drawings:

Fig. 1 is a fragmentary side view partly in section showing starting apparatus embodying the present invention.

Fig. 2 is a view similar to Fig. 1 showing the apparatus in position for cranking the engine.

Fig. 3 is a sectional view on the line 3—3 of Fig. 1.

The starting apparatus comprises an electric motor 20 having a field frame 21 to which is attached a motor switch 22 provided with a switch plunger 23 normally held in switch open-position by spring 24. The frame 21 is attached to a gear housing 25 provided with a bearing 26. The bearing 26 and a bearing not shown carried by the field frame 21 support an armature shaft 27 having a spirally splined portion 28 and provided with a stop-collar 29 which abuts a thrust washer 30 interposed between the collar 29 and the finished or plane surface 31 provided by the housing 25.

A motor pinion 32 is internally spirally

splined or broached to threadedly engage the splines 28 of shaft 27. Pinion 32 is adapted to mesh with and to drive a gear 33 driven by the engine, usually the form of flywheel gear. Pinion 32 is formed integrally with a hub or sleeve 34 which surrounds the shaft 27 and which carries two flanges 35 and 36 which define an annular groove 37. A pinion shifting lever including arms 38 and a yoke 39 is pivotally mounted upon a rod 40 supported by brackets 41 provided by the gear housing 25. The lever arms 38 are received by the groove 37. The flange 35 is normally maintained against a stop member 42 provided by shaft 27 by a spring having an intermediate portion 43 coiled about the rod 40, 70 having one end 44 resting upon the motor field frame 21 having the other end bearing against the lever 39.

Mechanism for operating the pinion shifting lever 38 includes a pedal 50 connected by a rod 51 with the free end of a leaf spring of the cantilever type having its fixed end secured by a rivet 53 to the yoke 54 of a lever which includes bifurcations 55 pivotally supported on rod 40. The lever arms 55 at their lower ends are joined by a stud or pin 56 which provides a pivot for a latch 57 having a hooked portion 58 adapted to extend through an aperture 59 in the pinion shifting lever yoke 39. The hook portion 85 is adapted to engage the surface of the yoke facing or adjacent the motor field frame 21. Latch 57 includes a lever arm 60 which is apertured to receive one end of a spring 61 which is shaped so as to extend over the rod 90 40 and between the lever arms 55. The spring 61 is secured at its fixed end by a screw 62 threadedly engaging the gear housing 25. The spring 61 normally biases the latch 57 in a counterclockwise direction so that normally motion will be transmitted from the lever arms 55 to the lever arms 38 when the former are moved in a counterclockwise direction.

The manner of using the invention is as follows:

To start the engine pedal 50 is pressed thereby causing the spring lever arm 52 to move in a counterclockwise direction thereby causing the latch 57 to move to the right 105 in Fig. 1 to move the lever arms 38 in a

counterclockwise direction and the motor pinion 32 into engagement with the engine gear 33. After gear engagement has been affected, the free end of the spring arm 52 will have moved sufficiently to engage the plunger 23 of switch 22 and to cause said plunger to move into switch closing position. This condition is shown in Fig. 2. The motor will then start and rotate the shaft 27 thereby causing the pinion 32 to be moved longitudinally against the stop 29, and thereafter, the pinion and shaft will rotate together to turn the engine gear 33.

During movement of the pinion 32 from the position shown in Fig. 1 to that shown in Fig. 2 the status of the spring 61 will be changed, and it will be reconditioned for biasing the latch 57 in the opposite sense so that, immediately the motor operates and pressure between the latch 57 and the lever yoke 39 is relieved, the spring 61 will be released to cause the latch 57 to move clockwise into the position shown in Fig. 2, this figure shows that the connection between the pedal 50 into pinion shifting lever 38 is interrupted. Consequently, when the engine becomes self-operative, the pinion 32 may be automatically demeshed by virtue of superior rotation of the engine gear relative to the pinion and the spirally splined connection between the pinion and motor shaft.

If the pinion 32 should be arrested during its endwise movement into mesh with the engine gear by reason of the ends of the pinion teeth striking the ends of the gear teeth, the apparatus will permit the closing of the motor switch although further movement of the pinion shifting lever 38 is prevented. In order to accomplish this the mechanism includes the leaf spring lever 52 which may bend regardless of arresting the movement of the lever 38 and the lever 55. Continued pressure upon the pedal 50 will therefore cause the free ends of the lever 52 to contact with the switch plunger 23 and move the latter into switch closing position. When this occurs the motor will turn the pinion 32 into registration with the engine gear 33. The additional energy which has been stored in the spring 52 by reason of bending it from its normal condition will be suddenly released to quickly move or "jump" the pinion 32 into mesh with the engine gear.

It is apparent therefore that the construction of starting apparatus of this type has been much simplified. Prior devices have included a pedal rod connected with a lever, pivoted on the starter frame, from which motion is transmitted to the pinion to move it endwise when it is desired to start the engine. Heretofore various forms of resilient connections have been interposed between the pedal lever and the pinion in order that the pedal may be operated to close the motor

switch regardless of the arresting of the motion of the pinion. By means of the present invention the construction has been simplified and cost of manufacture reduced by making the usual pedal lever a flexible lever in order that motion of the pedal to close the switch may be permitted in case of gear tooth abutment.

While the form of embodiment of the present invention as herein disclosed constitutes preferred forms, it is to be understood that other forms might be adopted, all coming within the scope of the claims which follow.

What is claimed is as follows:

1. Engine starting apparatus comprising, in combination, an electric motor; a motor switch; a pinion driven by the motor and adapted to be moved into engagement with a gear connected with the engine to be started; and means for moving the pinion into engagement with the engine gear and for closing the motor switch, said means including a lever having a pivoting portion and a flexible portion extending therefrom, means for transmitting motion to the pinion from the pivoting portion, and a pedal connected with the flexible portion adjacent its free end, the flexing of the lever permitting operation of the pedal to close the switch regardless of arresting the movement of the pivoting portion due to abutment of the pinion with the teeth of the engine gear.

2. Engine starting apparatus comprising, in combination, an electric motor, a motor switch having an actuator; a shaft operated by the motor; a pinion driven by the shaft and movable endwise thereupon into mesh with a gear connected with the engine to be started; a pinion shifting lever; a pedal lever including a pivoting portion pivoted coaxially with the pinion shifting lever and connected therewith, and including a flexible portion extending from the pivoting portion and adjacent the motor switch actuator; and a pedal connected with the flexible portion of the pedal lever.

3. Engine starting apparatus comprising, in combination, an electric motor; a motor switch having an actuator; a pinion driven by the motor and mounted for movement into mesh with a gear connected with the engine to be started; a lever having a pivoting portion and a flexible portion extending therefrom and adjacent the motor switch actuator; means connecting the pivoting portion with the pinion for shifting the latter into engagement with the engine gear and a pedal connected with said flexible portion.

4. Engine starting apparatus comprising, in combination, an electric motor, a motor switch; a pinion driven by the motor and mounted for movement into mesh with a gear connected with the engine to be start-

ed; an actuating member having a flexible portion, means connecting the actuating member with the pinion for shifting the latter into engagement with the engine gear; 5 and a pedal for closing the motor switch and for moving the actuating member, the pedal being connected with the flexible por-

tion at a location spaced from the location of the connection of the actuating member with the pinion shifting means. 10

In testimony whereof I hereto affix my signature.

GEORGE W. ELSEY.
